UNITED STATES PATENT OFFICE

HENRY K. HESS, OF WOLCOTT, NEW YORK

BOWLING ALLEY

Application filed March 15, 1932. Serial No. 598,958.

This invention relates to certain improvements in bowling alleys of the class set forth in my pending applications Serial No. 489,982 filed October 20th, 1930 and Serial No. 544,555

5 filed June 15th, 1931 in which the ball is thrown by hand from the proximal end along an upper runway and is returned from the distal end by power driven means along a lower runway onto a pin-supporting platform at the proximal ends of both runways for displacing the pins so that the pins may be served from or near the players' stand.

While the construction shown and described in my pending applications referred 15 to is highly efficient for balls of a certain diameter or size, no adequate provision was made therein for balls of widely varying diameters and one of the objects of the present invention is to enable the same apparatus 20 to be used with any of the standard size balls.

Another object is to provide means for returning the balls from the distal end to the proximal end of the alley and onto the pin-supporting platform with greater assurance, 25 reliability and force than has heretofore been practiced irrespective of the force with which the ball is thrown along the upper runway.

It will be understood that when the ball is deflected downwardly from the distal end of 30 the upper runway onto the adjacent end of the lower runway by the return deflector aided by the weight of the ball, the latter acquires a definite and appreciable momentum as it enters the lower runway.

35 One of the specific objects is to provide a power driven, high speed rotary drum with a resilient peripheral cushion arranged with its lower side in the path of the upper side of the downwardly deflected ball in such manner that the ball will automatically wedge itself between the drum and underlying portion of the return runway aided by its momentum and thereby to allow the drum to drive the ball along said return runway and onto 40 the pin supporting platform with approximately the speed of travel of the periphery of the drum.

Another object is to further assure this 45 wedging of the ball between the drum and underlying portion of the return runway by

allowing said underlying portion to yield downwardly against the action of suitable springs immediately upon the engagement of the ball with the drum.

Other objects and uses will be brought out 55 in the following description.

In the drawings:

Figure 1 is a top plan of a bowling alley embodying the various features of my invention.

Figure 2 is a side elevation of the same.

Figure 3 is an enlarged transverse vertical sectional view taken on line 3—3, Figure 1.

Figure 4 is an enlarged longitudinal vertical sectional view through the distal end 65 of the bowling alley taken on line 4—4, Figure 1.

Figure 5 is an enlarged transverse vertical sectional view through the adjustable bearings for the drum shaft taken on line 5—5, Figure 3.

Figure 6 is an enlarged longitudinal vertical sectional view, similar to that shown in Figure 4, except that it shows a modified construction of the yielding section of the floor of the lower runway.

Figure 7 is an enlarged longitudinal vertical sectional view through the proximal end of the bowling alley taken on line 7—7, Figure 1.

Figure 8 is an enlarged perspective view, partly in section, of a portion of the rotary ball-actuating drum showing more particularly the manner of fastening the cushioning tube to the periphery thereof.

Owing to the fact that this bowling alley is of the self-service type in which the pins are arranged upon a platform at the players' end of the alley and the ball is thrown along an upper runway and is automatically returned along an overlying runway onto the pin-supporting platform for displacing the pins, it is obvious that the alley may be made of standard width but of approximately half the length of the usual alley while the combined lengths of the upper and lower runways will be approximately equal to that of the standard alley thereby obtaining the full run of the ball within substantially half the 100

floor space occupied by the alley now in common use.

This bowling alley is designed to be made, sold and installed as a unitary article of manufacture and for this purpose consists of a main supporting frame having a bottom floor —1—, a super-posed floor —2—, opposite side walls —3— and opposite end walls —4— and —5—, all of which parts are preferably made of wood and rigidly secured to each other to form a unitary structure, but obviously may be made in longitudinal sections for convenience of transportation and installation.

15 This frame is, of course, elongated in one direction to approximately half the length of the usual bowling alley and is provided at one end with a players' platform —6— and a pin-supporting platform —7—, both 20 of which are rigidly secured to the adjacent or proximal end of the frame to form a unitary part thereof.

The bottom wall —1— is provided on its 25 upper side with a runway —8— extending the entire distance between the end walls —4— and —5— but having a relatively short portion of its distal end adapted to yield under pressure of the ball thereon.

This runway —8— is composed, as usual, 30 of a multiplicity of strips, preferably of hard wood glued or otherwise secured edge to edge to produce a smooth upper surface along which the ball is adapted to roll, said surface being slightly inclined from a horizontal 35 plane toward the proximal end of the alley to facilitate the return rolling of the ball from the distal end toward the proximal end and onto the pin-supporting platform —7— for displacing the pins therefrom.

40 The upper floor —2— serves to receive and support an additional runway —9— which is composed of relatively narrow strips of hard wood, glued or otherwise secured together edge to edge, to form a smooth upper surface which is preferably disposed in a horizontal plane and also extends the major portion of the length of the alley between the pin-supporting platform —7— and distal end wall —5—.

50 It will be noted, however, that the proximal end of the upper floor —2— and its runway —9— terminate some distance from the corresponding end wall —4— to form an intervening space —10— registering with the pin-supporting platform —7— for permitting the pins as —a— to be properly arranged upon said platform in such manner that they are readily visible to the player upon the platform —6—.

60 The side walls —3— of the frame extend vertically above the horizontal plane of the upper surface of the upper runway —9— to form guard rails —11— for preventing the displacement of the ball from said runway 65 when thrown upon the latter by the player

from the platform —6—, said guard rails being extended the entire distance between the platform —6— and distal end wall —5—.

The portions of the frame between the rails —11— and adjacent edges of the upper runway are provided with lengthwise grooves —2'— to guide the ball in case it should leave the runway.

70 The end wall —4— of the frame extends from the bottom floor —1— upwardly to the upper surface of the platform —6— and is provided with an inner substantially semi-circular deflecting surface —12— facing the distal end of the alley and extending from the adjacent end of the lower runway —8— a distance above the upper surface of the pin-supporting platform —7— somewhat greater than the diameter of the ball as —B— for deflecting the ball returning along the lower runway —8— upwardly onto the platform 85 —7— for displacing the pins —a— therefrom, as shown more clearly in Figure 7.

80 The distal end wall —5— is also provided with a substantially semi-circular inner deflecting surface —13— facing the proximal end of the alley and extending from the bottom floor —1— upwardly a distance above the horizontal plane of the upper surface of the upper runway —9— somewhat greater than the diameter of the ball —B— and in 90 spaced relation to the distal end of the floor —2— and upper runway —9— for deflecting the ball downwardly from the distal end of the upper runway downwardly onto the lower runway.

95 The players' platform —6— is disposed in a horizontal plane slightly above that of the upper runway —9— and closely adjacent the end wall —4— so that the player standing upon the platform —6— may throw the ball 100 across the intervening pin space —10— and onto the proximal end of the upper runway —9— so that the ball leaving the distal end of the upper runway will be deflected by the concaved surface —13— downwardly onto the adjacent end of the lower runway to be driven toward the proximal end by power driven means, presently described.

105 The pin-supporting platform is mounted in the main supporting frame in a horizontal 115 plane a distance below the upper surface of the runway —9— corresponding approximately to the height of the pins —a— when arranged in an upright position on said platform, the latter being also spaced a distance 120 above the lower runway —8— somewhat greater than the diameter of the ball —B— to allow free travel of the latter along the lower runway and upwardly along the concave surface —12— onto the platform —7— 125 for displacing the pins therefrom.

130 The floor as —7'— supporting the platform —7— is extended rearwardly some distance beyond the vertical plane of the front end of the upper runway —9— to form a pocket

—14— and is connected to the upper floor —2— by a partition —15— which serves as a buffer or limiting stop for the ball —B— and pins —a— which may be displaced from the platform —a—, as shown more clearly in Figure 7, it being understood that the extension —7— will be spaced a sufficient distance above the lower runway —8— to allow the ball to pass freely thereunder without contact therewith.

Suitable power driven means is provided for driving the ball along the lower or return runway —8— with sufficient force and velocity to carry it up the deflecting surface —12— and upon the pin-supporting platform —7— for displacing the pins and for this purpose a horizontal shaft —16— is extended transversely of the frame through vertically elongated openings —17— in opposite sides thereof and has its opposite ends journaled in suitable bearings —18— which are adjustable vertically in supporting standards —19— at the outer sides of and independent of the frame to rest upon the floor of the building in which the bowling alley is installed, as shown in Figures 1, 2, 3 and 5.

Each of these standards —19— is provided with vertically elongated openings —20— at opposite sides of the adjacent bearing —18— for receiving threaded bolts or screws —21— having their inner ends engaged with opposite sides of the bearing —18— and held in their adjusted position by lock nuts —22—.

Each of the standards —19— is also provided with vertically spaced cross bars —23— and —23'— arranged in vertically spaced relation below and above the shaft —16— and is provided with threaded openings —24— for receiving vertical adjusting screws —25— and —25'— which are engaged with the lower and upper faces of the adjacent bearing —18—, as shown more clearly in Figure 5, said screws being held in their adjusted position by lock nuts —26—.

The shaft —16— is located between the distal ends of the lower and upper runways —8— and —9— in spaced relation thereto and constitutes a part of a rotary drum —27— which is composed of opposite half sections —28— of wood or equivalent material secured together around the shaft and concentric therewith by bolts or screws —29—, as shown more clearly in Figures 3, 4, 6 and 8, aided by a key —30— which is seated in a keyway —31— in the shaft as shown in Figure 8.

This drum extends from side to side of the main supporting frame or entirely across the upper surface of the lower runway —8— and is provided with a resilient peripheral cushion —32— consisting in this instance of a rubber hose through which is threaded a wire —33—, said hose with the wire therein being wound spirally around the periphery of the drum sections —28— with their helices in abutting relation and their opposite ends

rigidly secured to the periphery of the sections —28— by staples —34— or equivalent fastening means.

The wire —33— passing through the tubular cushion —32— is of somewhat smaller diameter than that of the interior of the tube so as to allow full resiliency of the tube, the wire serving to hold the tube against undue displacement from the sections —28— by centrifugal force and also aiding in keeping the helices of the tube in proper relation to each other.

One end of the shaft —16— is provided with a pulley —35— which is connected by a belt —36— to another pulley —37— on one end of the shaft of an electric motor —38— to which latter current may be supplied from any available source of electricity, as for example, through the medium of the usual electric plug and socket, not shown.

The purpose of the adjusting screws —21— in the drum-supporting standards —19— is to permit said shaft and drum to be adjusted to a position at right angles to the longitudinal centers of the lower and upper runways —8— and —9—, for properly directing the ball.

The object of the vertical adjusting screws —25— and —25'— is to permit the shaft —16— and drum —27— to be adjusted to a position parallel with the upper surfaces of the lower and upper runways —8— and —9— and also to permit the shaft and drum to be adjusted vertically relatively to the lower runway as may be required to operate upon balls of different standard diameters, the ball illustrated in the drawings being of the largest size commonly used, and, therefore, the drum —27— is shown as adjusted to its maximum height above the upper face of the lower runway —8— to allow the larger ball to wedge between the periphery of the elastic cushion —32— and underlying portion of the lower runway, as shown more clearly in Figures 4 and 6.

In order to assure this wedging action of the ball between the lower side of the drum —27— and underlying portions of the lower runway —8—, the latter is provided with a relatively short yielding section —8'— which is arranged directly under the drum —27— to extend the full length thereof and is normally disposed with its upper face a distance below the lower face of the drum slightly less than the diameter of the ball —B—.

As shown in Figure 4, the distal end of the yielding section —8'— is hinged at —39— to the end wall —5— with its upper face substantially coincident with the lower portion of the curved deflecting surface —13—, the opposite end of said section being yieldingly supported by one or more coil springs —40—, as shown more clearly in Figures 3 and 4.

In Figure 6, I have shown a modified means of supporting the yielding section —8'— in

which the distal end of the section is supported upon one or more coil springs —40— while the opposite end is hinged at —39— to the distal end of the lower floor —1— and corresponding runway —8—, the distal end of the section —8'— or —8''— being adapted to engage a stop —42— for limiting its upward movement by the springs —40'—.

It is now clear that when the ball leaves the distal end of the upper runway —9— and is deflected downwardly by the adjacent curved surface —13— on the end walls —5— aided by its own gravity and momentum, it will wedge in between the lower face of the resilient cushion —32— and upper face of the yielding platform —8'— or —8''— whereby the continuous rotating drum will cause the ball —B— to be driven along the lower runway —8— toward the proximal end 15 of the alley with sufficient force to carry it up the curved deflecting surface —12— and onto the pin-supporting platform —7— for displacing the pins —a— as indicated more clearly in Figure 7, it being understood that 20 the shaft —16— and drum —27— will be driven at high speed by the electric motor —38— through the medium of the belt —36—.

The pins —a— will be arranged upon the platform —7— in the usual order shown by 30 the spots —7''— thereon in Figure 1 so that all of the pins will be clearly visible to the player standing upon the platform —6— which is provided at one side with a rack —43— having a series of holes —44— for receiving the pins when not in use.

Operation

The player standing upon the platform —6— visually selects the particular pin or pins which it is desired to displace from the assembly on the platform —7— and then throws the ball in line with the selected pin or pins across the upper ends of the assembled pins and onto the upper runway —9— along 45 which it rolls beyond the distal end thereof and into engagement with the curved deflecting surface —13— of the end wall —5— where it is deflected downwardly onto the yielding section —8'— of the lower runway 50 —8— to wedge against the lower face of the cushioned periphery of the drum —27— which is then rotating at high speed in the direction indicated by arrow X, Figures 4 and 6.

Immediately upon the wedging contact of the ball —B— with the yielding cushion —32— of the drum and the section —8'— or —8''—, the frictional contact between the cushion —32— and the periphery of the ball 60 will cause a slight depression of the yielding section —8'— or —8''— against the action of the springs —40— or —40'—, thus permitting the frictional contact of the yielding cushion —32— with the drum to drive the ball along the lower runway with sufficient

force to carry it upwardly along the curved deflecting surface —12— of the proximal end wall —4— and onto the pin-supporting platform —7— for displacing the pins with the assurance that the ball will strike the preselected pin or pins providing the ball is directed along the upper runway in alignment with said preselected pin or pins so that the play will depend upon the ability of the player to cause the ball to travel along the upper runway in alignment with said preselected pin or pins in which case the action of the drum upon the ball will affect the displacement of the preselected pin or pins.

One of the advantages of this particular construction is that the pins upon the platform are clearly visible to the player by reason of the fact that they are directly in front of the players' stand and, therefore, easily visible so that the expert player may select the particular pin or pins to be displaced and direct the ball along the upper runway in line with said preselected pin or pins.

A further advantage is that the distance between the player and distal end of the upper runway is relatively short or half the length of the usual alley so that he may more easily determine the accuracy of his play when the ball leaves the upper runway with the assurance that when the ball comes in contact with the drum it will be returned along the lower runway and onto the pin-supporting platform in the same line with which it was propelled along the upper runway or in line with the point of the distal end of the upper runway at which the ball leaves the latter.

In other words by making the upper and lower runways relatively short or approximately half the length of the usual runway 105 permits greater accuracy in the plays according to the skill of the player with less liability of wavering of the ball from the directed course as is frequently the case in the longer or usual runways.

This accuracy is greatly facilitated by reason of the resilient cushion on the periphery of the drum and the yielding underlying section of the lower runway which renders the wedging of the ball between the lower side of the drum and yielding section and resultant return drive of the ball by the drum more positive than would be otherwise possible.

It will also be noted that the ball may be caused to move at a relatively slow rate of speed along the upper runway with the assurance that when it is discharged therefrom it will be brought into immediate contact with the periphery of the drum to be returned thereby with considerable force and velocity along the lower runway.

The construction and operation described is particularly simple, practical and highly efficient, but obviously various changes may

be made in the detail construction without departing from the spirit of the invention.

What I claim is:

1. In a bowling alley having an upper runway along which the balls are thrown by hand, and a lower runway underlying the upper runway along which the ball is returned, means for deflecting the ball from the distal end of the upper runway onto the adjacent end of the lower runway, in combination with power driven means between the distal ends of the lower and upper runways for propelling the ball along the lower runway, a pin-supporting platform at the proximal end of said runways, and means for deflecting the ball from the proximal end of the lower runway onto the pin-supporting platform for displacing the pins, said lower runway having a portion thereof directly under the propelling means adapted to yield under pressure of the ball when the latter is engaged by the propelling means to assure the propulsion of the ball by said propelling means.
2. In a bowling alley of the character described, a runway for the ball having a yielding section, and a rotary power-driven drum directly over said section for engaging the ball and thereby depressing the yielding section to allow the ball to be driven along the runway by the drum.
3. In a bowling alley of the character described, a runway for the ball having a yielding portion, and a power-driven rotary drum in opposed spaced relation to the yielding portion of the runway to allow the ball to wedge between the drum and yielding portion and to be propelled along the runway by the drum.
4. In a bowling alley of the character described, a runway for the ball, a power-driven rotary drum above a portion of the runway in spaced relation thereto, a normal distance slightly less than the diameter of the ball for engaging said ball, said portion of the runway being yielding to allow the ball to depress the same when the ball is engaged by the drum and thereby to permit the drum to drive the ball along the runway.
5. A bowling alley as in claim 2 in which the drum is provided with a resilient peripheral cushion adapted to frictionally engage the ball.
6. A bowling alley as in claim 2 in which the drum is provided with a peripheral elastic tube spirally wound thereon and secured thereto for frictionally engaging and driving the ball.
7. A bowling alley as in claim 2 in which the yielding section of the runway is hinged at one end and has its other end spring-pressed toward the drum.
8. A bowling alley as in claim 2 in which means is provided for adjusting the drum to

ward and from the yielding section of the runway.

9. In a bowling alley of the character described, a runway for the ball, a power-driven rotary drum above the runway for engaging and driving the ball along said runway, and means for adjusting the drum toward and from the runway to operate upon balls of different diameters.

In witness whereof I have hereunto set my hand this 14th day of March 1932.
